UNITED STATES PATENT OFFICE.

JOHN H. FELTHOUSEN, DECEASED, LATE OF YORK, PENNSYLVANIA; BY BIRDIE J. FELTHOUSEN, ADMINISTRATRIX, OF BALTIMORE, MARYLAND, ASSIGNOR TO S. MORGAN SMITH COMPANY, OF YORK, PENNSYLVANIA, A CORPORATION OF PENNSYLVANIA.

TURBINE INSTALLATION.

Original application filed December 20, 1919, Serial No. 346,253. Divided and this application filed October 30, 1923. Serial No. 671,782.

To all whom it may concern:

Be it known that JOHN H. FELTHOUSEN, now deceased, formerly a citizen of the United States, lately residing at York, in the county of York and State of Pennsylvania, BIRDIE J. FELTHOUSEN administratrix of the estate of the said JOHN H. FELTHOUSEN, did during his lifetime invent certain new and useful Improvements in Turbine Installations, of which the following is a specification.

This invention relates to turbine installations, and particularly to a structure providing for disposition of increased power 15 turbine wheels in a flume having restricted dimensions or side walls, which cannot be decreased in thickness to enlarge the width of the flume to receive the usual form of supply scroll. At the present time there are 20 a number of flume structures comprising a plurality of flumes in parallel relation, separated by partition walls of a thickness to sustain the water pressure without liability of breaking through, and having installed 25 therein turbine wheels of comparatively low power, and in other structures the flumes are located under superstructures and serve as parts of the foundation supporting means and will not admit of width enlargement 30 without impairing and weakening the foundation, and consequently, seriously affecting the superstructures thereover. In these existing restricted and limited flume structures it is frequently desirable to substitute in- 35 creased power turbine wheels for turbine wheels of a much lower power, to utilize the water power to the fullest extent and greatest efficiency. In all of the substitute installations of this character the increased 40 power turbine wheels will be installed at a proper elevation for minimum head, and the relative velocities thereof are not affected by a change of head. By the installation embodying the features of the in- 45 vention the water is supplied to the wheel gates from one direction and always flows in the same direction over the turbine wheel and enters the wheel gates at different peripheral points with the same velocity rela-

tively to the number of wheel gates supplied, so that the water supplied to the upstream portion of the gates will not affect the downstream portion of the gates, or substantially each half of the wheel will be separately supplied. The invention further 55 contemplates an installation whereby with the same head of water the inlet to the turbine or wheel is effected at opposite points, with uniform velocity relatively to the number of gates supplied. More specifically, 60 and as a preferred organization embodying the features of the invention, parts of complete scroll inlets or water supplies are used with the same maximum efficiency that would be derived by the use of a complete 65 scroll if the use of the latter water supply or inlet means was permissible.

The invention consists in the construction and arrangement of the several parts which will be more fully hereinafter described and claimed.

In the drawings:

Fig. 1 is a vertical cross sectional elevation of a turbine and usual accessories embodying the features of the invention;

Fig. 2 is a horizontal section on the line 2—2, Fig. 1, showing parts broken away; and

Fig. 3 is a section on the line 3—3, Fig. 2.

This application embodies subject-matter 80 divided out of the application of John H. Felthousen, deceased, Serial No. 346,253, filed December 20, 1919, and now Patent No. 1,489,994, April 8, 1924.

The numeral 5 designates a flume, 6 the 85 runner or vertically disposed type of wheel secured as usual to the lower end of a power shaft 7, and 8 the usual wheel gates, which are operated by well known means to open and close the same as may be found necessary. The runner or wheel 6 discharges into a draft tube 9, which may be of any approved type. The frame or enclosing casing 10 for the turbine or wheel as shown is of the usual construction. All of these parts 90 are well known and form no part of the present invention, being shown solely to demonstrate the practicability of the features 95

of the invention. The turbine installation illustrated by the drawings is also shown as having a generator 11 directly connected to, or operatively associated with, the turbine 5 or power shaft 7, and gate operating means consisting of a shaft 12 attached to the usual gate ring 13 and actuating means 14 is also shown, the generator 11 and actuating means 14 being disposed on a generator floor 15. 10 The generator is not included in the features of improvement, being illustrated simply to indicate a complete turbine structure or installation as adopted in modern organizations of this character.

15 The improved features of the invention as shown are preferably produced by the use of concrete or cement material in the flume, but it is intended to construct the improved features of other material, one of the main 20 objects being to extend the improved structure from one side wall to the other side wall of the flume. The improvement resides essentially in a double partial scroll inlet, consisting of two partial scroll units 25 16 and 17 in reverse positions, and usable with water continually flowing in one direction thereto and over the same, the water being prevented from passing down through the top portion of the wheel casing or indiscriminately around the peripheral edge of 30 the casing to the wheel gates. The concrete or cement structure 18, in which the reverse- 35 arranged partial scroll units 16 and 17 are formed, is provided with front and rear horizontally disposed projecting ledges 19 and 20, which overhang the inlets to the scroll units 16 and 17 below the same, these ledges forming the top closures or walls 40 for the scroll unit inlets. In the center of the concrete or cement structure 18 a space 21 is formed, and therein the wheel or runner 6 together with the casing 10 and gates 8 are disposed and supported and held in operatively fixed position over the draft 45 tube 9 with the shaft 7 extending upwardly through the center of said space, as shown by Fig. 1. Each of the partial scroll units 16 and 17 is hollow and has a scroll-like interior contour continuing regularly from the 50 maximum dimensions at the inlet 22 thereof to the terminal 23 of minimum dimensions. The terminals 23, as clearly shown in full and dotted lines by Fig. 2, are angular and continue inwardly fully to the periphery 55 of the wheel, or to the gate openings of the casing, and serve as separating partitions to prevent the water flowing into different portions of the wheel from taking any other course than that particularly provided in 60 accordance with the features of the invention. The inlet of the unit 16 under the ledge 19 faces the upstream direction of flow of the water, and the inlet of the unit 17 is in the rear and receives the water 65 thereinto in a downstream flowing direction,

the entrance of the water into the inlets of these units being clearly indicated by the arrows 24 and 25 and which show that the water enters the wheel gates at all points around the wheel periphery in the direction 70 of rotation of the wheel runner. The water, always flowing in the same direction, enters the wheel gates at opposite points with proportionate volume and uniform velocity 75 relatively to the number of gates supplied, so that there is no retardation of operation of the wheel at any part thereof, with the advantageous result that the full power of the water flowing continually in one direction to and over the units 16 and 17 and 80 the wheel is conserved within the restricted width of the flume, which will not permit of an enlargement sufficient for installation of the usual complete scroll supply structure forming part of high power wheels. 85

The concrete structure 18, or the analogous covering element of whatever material used that extends from one side wall to the other of the flume, may be of suitable length, but in all formations the rear edge of the ledge 20 will be located at a distance in advance of the rear end wall 26 of the flume, so as to permit the water that flows over this covering element and the top of the casing 10 of the turbine to have 90 a free passage downwardly to the inlet of the rear partial scroll unit 17. The covering element in which the turbine is disposed will also be at such elevation above the bottom of the flume as to produce a 95 maximum supply of water through both partial scroll units 16 and 17. Moreover, the partial scroll units 16 and 17 are of the same general dimensions, so that the number of wheel gates that are open to each 100 unit will be supplied with a like quantity of water. It will also be seen that the terminal 23 of each partial scroll unit has opposed concave surfaces 23^a and 23^b, and that the one terminal or angular partition 110 23 is located in advance of the other, to effect the partial scroll formation of the two units 16 and 17 having equal dimensions. It will further be seen that one-half 115 of the gates 8 are open for supply in each scroll unit and that the water entering the unit 16 and supplying the forward group of gates cannot reach, and does not in the least affect, the rear group of gates to which the water is supplied through the rear partial scroll unit 17. By this means the runner or wheel 6 is caused to rotate continuously in one direction, the speed of rotation of, and the power generated by, the runner being materially augmented by the 120 water separately entering the forward and rear groups of gates.

The water passing downwardly through the runner 6 is discharged as usual into the draft tube 9 and carried away any distance 130

from the flume, or deposited in a pit, race or other conveying means, and it will be understood that any form of draft tube adapted for the purpose may be used.

5 As an incidental and advantageous feature of construction, a cover or partition plate 27 is applied above the wheel space or seat 21 between the units 16 and 17, or over the top of the turbine casing, as shown by

10 Figs. 1 and 3, this plate being removed in Fig. 2. The purpose of this horizontal cover or partition plate 27 is to prevent the water from eddying or churning over and adjacent to the top of the wheel casing or housing.

15 The preferred form of the installation has been particularly described as especially adapted for disposition in a flume wherein the water continually flows in one direction, as for instance, towards the end wall 26 of the flume, but it is intended to install this partial scroll supply means in reasonable and permissible equivalent forms in other water supply flumes or the like wherein the water may not flow in one direction and to 25 which the improvements may be operatively applicable.

What is claimed as new is:

1. In a turbine installation, the combination with a flume, of a wheel organization having water operated driving means, and a closure structure extending fully across the flume between the side walls thereof and having the wheel organization enclosed therein, the wheel organization and closure structure being submerged in the flume, the said closure structure being provided with reversely arranged partial scroll units cooperating with the front and rear portions of the said driving means for controlling a proportional supply of water to different portions of the driving means to maintain free rotation of the latter in one direction.

2. In a turbine installation, the combination with a flume, of a wheel organization having rotating driving means and controlling gates for the latter, and a closure structure extending fully across the flume from one side wall to the other and over which the water flows and having the wheel organization disposed therein, said closure structure being provided with reversely arranged supply inlet means at the front and rear portions of the wheel organization and completely enclosing portions of the periphery of the said organization for controlling proportional entrance of water in reverse directions relatively to the gates and driving means to maintain a free and uniform rotation of the driving means in one direction, the water being caused to flow downwardly and forwardly in entering the rear inlet means.

3. In a turbine installation, the combination with a flume, of a horizontally disposed closure structure extending fully across from

one side wall to the other side wall of the flume and having a wheel organization with a rotating water operated driving means therein and controlling gates for the said driving means, the said closure being provided with reversely arranged supply inlets at the front and rear with portions of the closure overhanging the same and completely enclosing portions of the periphery of the wheel organization for controlling entrance of the water proportionally through different groups of the gates to maintain a free and uniform rotation of the driving means in one direction.

4. In a turbine installation, the combination with a flume, of a horizontally disposed closure structure extending across the flume from one side wall to the other of the latter and having a wheel organization with rotary water operated driving means disposed therein, the closure structure having front and rear separated partial scroll inlets completely enclosing opposite portions of the periphery of the wheel organization to effect a proportional inlet of water to different peripheral portions of the wheel in reverse directions and preventing the water from one inlet affecting the water of the other inlet, the water entering the front inlet in a forward direction and the water entering the rear inlet being caused to flow downwardly and forwardly.

5. The combination with a flume, of a closure structure extending across the flume from one side wall to the other of the latter and having a wheel organization with rotary water operated driving means disposed therein, the closure structure being provided with means for completely enclosing different peripheral portions of the wheel organization and separating and reversely directing the water into said peripheral portions.

6. The combination with a flume, of a horizontal closure structure extending fully across the width of the flume and having a turbine installed therein and also provided with overhanging front and rear ledges and means for completely enclosing and separating different peripheral portions of the turbine and directing and supplying the water thereinto with the same velocity relatively to the said different peripheral portions of the turbine.

7. The combination with a flume, of a closure structure extending fully across the width of the flume and having a turbine installed therein, one end of the closure structure being spaced a distance from the end wall of the flume so that the water may flow over the structure and turbine installation to the rear of the latter, the closure structure having supply inlet means completely enclosing different peripheral portions of the turbine and directing and supplying the water thereinto with the same velocity rela-

tively to the said different peripheral portions of the turbine.

8. The combination with a flume, of a closure structure extending across the width of the flume below the water level of the latter and having a turbine with discharge means installed therein, the closure structure having supply inlet means completely enclosing different peripheral portions of the turbine and directing and supplying water thereinto with the same velocity relatively to the said different peripheral portions of the turbine.

9. The combination with a flume, of a closure structure extending across the width of the flume below the water level in the latter and terminating a distance from the end wall of the flume to form a passage for the downward course of the water, the closure structure having a turbine with discharge means installed therein and also having supply inlet means completely enclosing different peripheral portions of the turbine and directing and supplying water thereinto with the same velocity relatively to the said different peripheral portions of the turbine.

10. The combination with a flume, of a closure structure extending across the width of the flume below the level of the water in the latter and having a turbine with discharge means installed therein, the said structure having front and rear overhanging ledges adjacent to reversely disposed supply inlet means completely enclosing different peripheral portions of the turbine to regularly direct and supply the water with the same velocity relatively to the said different peripheral portions of the turbine.

11. The combination with a flume, of a submerged turbine having a runner and discharge means, the turbine being enclosed by a horizontal closure extending fully across the width of the flume, said closure being provided with front and rear overhanging ledges and reversely arranged water inlet means across the front and rear portions of the periphery of the turbine, the front and rear inlet means being separated by inwardly projecting portions of the flume located at opposite sides of the closure, the said closure also completely enclosing different portions of the periphery of the turbine to direct and supply the water to the two inlets in uniform quantity and velocity to operatively engage opposite parts of the turbine.

12. The combination with a flume, of a closure structure extending fully across the width of the flume in a horizontal plane and formed at the front and rear with reversely arranged partial supply scrolls separated from one another by opposite side inwardly projecting portions of the flume, and a turbine including a runner and draft tube installed within and enclosed by the said struc-

ture between the partial scrolls, the separation of the partial scrolls preventing the water flowing into the one from affecting the water flowing into the other.

13. The combination with a flume, of a closure structure extending across the width of the flume below the water level of the latter and having a turbine with discharge means centrally installed therein, the closure structure having partial scroll supply inlet means in reverse positions relatively to and completely enclosing different peripheral portions of the turbine for properly directing and supplying the water to the latter, each partial scroll supply inlet means being provided with an inwardly extending converging partition for separating both scroll inlet supply means.

14. The combination with a flume, of a closure structure extending across the width of the flume below the water level of the latter and having a turbine with discharge means centrally installed therein, the closure structure having partial scroll supply inlet means in reverse positions relatively to and completely enclosing different peripheral portions of the turbine for properly directing and supplying the water to the latter, each partial scroll supply inlet means being provided with an inwardly extending converging partition for separating both scroll inlet supply means, the one partition being in advance of the other.

15. The combination with a flume, of a closure structure extending fully across the width of the flume and having a turbine with discharge means installed and enclosed therein, the turbine being provided with a runner and a plurality of gates to control the entrance of water into the runner, the closure structure having spirally arranged supply inlet means completely enclosing different peripheral portions of the turbine and directing and supplying the water in separated and equal quantities and with the same velocity to the same number of gates and uniformly guiding the water in the direction of rotation of the runner.

16. In a turbine installation, the combination with a flume having a rear closed wall, of horizontally disposed means extending across the flume from one side wall to the other thereof and terminating at its rear portion a distance from the rear closed wall of the flume, the said means having opposed reversely arranged partial scrolls at the front and rear thereof separated from one another by inwardly projecting side portions of the flume, and a wheel organization having water operated driving means located within the said means and opposite portions thereof exposed to the partial scrolls, the said horizontally disposed means and wheel organization being submerged in the

flume and the water flowing towards the rear closed wall entering the front of the wheel organization and the portion of the water flowing over the said horizontally disposed means and wheel organization passing downwardly in the space between the rear terminal of the said horizontally disposed means and the end wall of the flume and

flowing forwardly into the rear portion of the wheel organization.

In testimony whereof I have hereunto set my hand.

BIRDIE J. FELTHOUSEN,
Administratrix of the estate of John H.
Felthousen, deceased.
